(57) CLAIM

We claim the ornamental design for an integrated tilt/sash lock assembly, as shown and described.

DESCRIPTION

FIG. 1 is a perspective view of the integrated tilt/sash lock assembly of the present invention;

FIG. 2 is a top plan view of the integrated tilt/sash lock assembly shown in FIG. 1;

FIG. 3 is a front elevation view of the integrated tilt/sash lock assembly shown in FIG. 1;

FIG. 4 is a left side elevation view of the integrated tilt/sash lock assembly shown in FIG. 1;

FIG. 5 is a right side elevation view of the integrated tilt/sash lock assembly shown in FIG. 1;

FIG. 6 is a rear elevation view of the integrated tilt/sash lock assembly shown in FIG. 1;

FIG. 7 is a bottom view of the integrated tilt/sash lock assembly shown in FIG. 1;

FIG. 8 is a perspective view of an alternative embodiment of the integrated tilt/sash lock assembly of the present invention;

FIG. 9 is a top plan view of the integrated tilt/sash lock assembly shown in FIG. 8;

FIG. 10 is a front elevation view of the integrated tilt/sash lock assembly shown in FIG. 8;

FIG. 11 is a left side elevation view of the integrated tilt/sash lock assembly shown in FIG. 8;

FIG. 12 is a right side elevation view of the integrated tilt/sash lock assembly shown in FIG. 8;

FIG. 13 is a rear elevation view of the integrated tilt/sash lock assembly shown in FIG. 8;

FIG. 14 is a bottom view of the integrated tilt/sash lock assembly shown in FIG. 8;

FIG. 15 is a perspective view of another alternative embodiment of the integrated tilt/sash lock assembly of the present invention;

FIG. 16 is a top plan view of the integrated tilt/sash lock assembly shown in FIG. 15;

FIG. 17 is a front elevation view of the integrated tilt/sash lock assembly shown in FIG. 15;

FIG. 18 is a left side elevation view of the integrated tilt/sash lock assembly shown in FIG. 15;

FIG. 19 is a right side elevation view of the integrated tilt/sash lock assembly shown in FIG. 15;

FIG. 20 is a rear elevation view of the integrated tilt/sash lock assembly shown in FIG. 15; and,

FIG. 21 is a bottom view of the integrated tilt/sash lock assembly shown in FIG. 15.

Features shown in broken lines in the drawings are not part of the claim.
